UNITED STATES PATENT OFFICE.

GUY R. PRICE, OF DETROIT, MICHIGAN.

EXPLOSION-ENGINE.

978,936.

Specification of Letters Patent. Patented Dec. 20, 1910.

Application filed February 28, 1910. Serial No. 546,281.

To all whom it may concern:

Be it known that I, GUY R. PRICE, a citizen of the United States, and a resident of Detroit, in the county of Wayne and State of Michigan, have invented a new and useful Explosion-Engine, of which the following is a specification.

These improvements relate to internal combustion engines, and the object of this invention is to produce an engine having a plurality of explosion chambers and pistons in one cylinder, one of the pistons being adapted to receive an impulse from an explosion in one explosion chamber so that all the pistons may acquire momentum for compressing the explosive charges in other explosion chambers.

A further object of this invention is to provide an engine requiring a flywheel of minimum weight.

In the accompanying drawings of an explosion engine embodying my invention, Figures 1 and 2 are vertical cross sections on the lines 1-1 and 2-2 of Fig. 3 respectively. Fig. 3 is a plan, and Fig. 4 is a horizontal cross section on the line 3-3 of Fig. 1.

Similar reference characters refer to like parts throughout the several views.

The usual four cycle explosion engine requires a flywheel of considerable weight, because the momentum of the flywheel is depended upon to compress the explosive charge during the fourth cycle of movement. The engine shown in the drawings is so constructed that the compression prior to the main explosion is effected by a preliminary explosion. While two pistons, and therefore, three explosion chambers are shown, the number may be varied as desired. The engine will have less power if the lower piston is omitted but the operation would be substantially the same.

The crank case 1, crank shaft 2, gears 3 and 4, cam shaft 5, and flywheel 6 are of any desirable design and form no part of this invention, and are therefore shown in a conventional manner. The upper face of the crank case is properly machined to engage a machined flange 7 on the cylinder casting, the screws 8 being employed to hold the parts together. The cylinder casting is formed with an inner shell 9 or cylinder proper; an outer shell 10 or water jacket; separated from the inner shell by the passages 12; and the valve chambers 13, 14, 15

and 16. A cylinder head 17 of any desired design closes the upper end of the cylinder, within which are slideable the pistons 18 and 19 connected by the piston rod 20. A connecting rod 21 extends between the pin 22 of the piston and the crank pin 23. Either part of the bore of the cylinder may be of greater diameter than the other, the difference being just sufficient to permit the auxiliary head 24 to be secured in position in any desirable manner, screw-threading being shown. This head is preferably formed of two disks 25, connected by a threaded ring 26 having apertures 27 to permit free flow of the cooling liquid. Bushings 28 may be screwed into the heads and removed and replaced as they become worn, thus insuring a proper fit around the piston rod at all times. Ports 29 connect the apertures 27 to the passages 12 in the wall of the cylinder.

On the side of the engine, wherever practicable, may be mounted a carbureter 30, from which pipes 31 extend to the ports 32, 33 and 34. Mounted in the valve chamber 16 (Fig. 2) is a guide 35 for the stem 36 of the valve 37. A light spring 38 normally holds the valve on its seat. A port 39 connects to the engine and a spark plug 40 will cause an explosion at the proper time. This valve will open against the pull of the spring at each alternate upward movement of the piston 18. A cover 41 closes the opening wherethrough the spring may be inspected, and a head 42 closes the bore of the chamber.

The valve chamber 15, (Fig. 1) is preferably bored from both ends and fitted with guides 42 and 43 for the valve stem 44, preferably in two pieces joined by the coupling 45. Springs 46 on the stem normally hold the valves 47 and 48 on their seats. On the intake stroke these valves are lifted from their seats and permit the explosive vapor to enter the cylinder through the ports 49 and 50. A small roller 51 is preferably mounted at the lower end of the stem 44 and rides on the cam 56 on the cam-shaft 5. The lower end of this valve chamber is fitted with a guide-head 52 and at the upper end is a head 53. A cover 54 may be removed to permit the parts to be assembled. A spark-plug 55 is secured adjacent the port 49, preferably in the head 53, while the second spark-plug 55 can be screwed into the wall 110 of the chamber adjacent the port 50.

The exhaust of the burned gases may be

controlled by automatic or cam-operated valves. In Fig. 2 the valve chamber 14 is shown fitted with upper head 60, guides 61, 62 and 63 for the stem 64, and lower guide-head 65. A roller 66 at the lower end of the stem rests on the cam 67 and the two parts of the stem are shown joined by the coupling 68. The two valves 69 and 70 are held on their seats by the springs 71. When the valves are opened by the cam 67, the burned gases will pass from the cylinder by means of the ports 49 and 50 into the chamber and out through the exhaust pipes 74. Upon removing the cover 75 access is obtained to the stem 64 and coupling 68.

In Fig. 1 is shown the automatic exhaust mechanism of the intermediate explosion chamber. In the valve chamber 13 is mounted a guide cylinder 80, and a guide 81, and the ends are closed by the heads 82 and 83. A valve stem 84 has a valve 85 at its lower end, normally held on its seat by the spring 86. At the upper end is a piston 87, while a collar 88, intermediate the ends has a finger 89 engaged by a lip 90 at the upper end of the spring 91. The exhaust pipe is marked 92, and access to the springs is obtained by removing the plate 93. The upward movement of the piston 18 under the force of the explosion between this piston and the head 24 compresses the charge above the piston, but the stiffness of the spring 86, aided by the upward pressure of the lip 90 on the finger 89 is sufficient to hold the piston 87 against this pressure. But when an explosion follows the compression of the charge above the piston 18, the pressure of the gases is sufficient to force down the piston 87, the finger 89 forcing past the lip 90, and the valve 85 leaving its seat. The valve 85 will therefore permit the waste gases between the head 24 and piston 18 to pass out during this downward movement of the piston, and this valve will be held open so long as the pressure on the piston 87 is greater than the upward pressure of the spring 86 and the resisting pressure of the lip 90 on the finger 89. When the down stroke of the piston is completed, and the exhaust valve 69 opened, the pressure on the piston 87 will end and the spring 86 will press the valve 85 onto its port.

The two pistons 18 and 19 on the same piston rod are forced down by the simultaneous explosions of the charges of explosive vapors immediately above them. The valves 47, 48, 69 and 70 have the usual movements of valves of four cycle engines. The explosion between the piston 18 and the head 24 occurs at the time the pistons move upward to compress the explosive charges. As the flywheels of four-cycle engines are usually made heavy in order to store energy sufficient to accomplish such compression, much weight can be saved as just this step

is now taken care of by the explosion beneath the piston 18.

Many changes in the details and proportions can be made by those skilled in engine designing without departing from the spirit 70 of my invention. Thus the valve mechanisms shown may be interchanged or duplicated or replaced by others.

The operation of the engine is as follows. The drawings show the parts just as the exploded vapor between the piston 18 and the head 24 is forcing up the pistons and thus compressing the charges above the pistons. At the end of the upward stroke, the charges will be exploded and the pistons forced 80 down, and at the same time, the valve 85 will be moved off its seat to permit the intermediate explosion chamber to be scavenged. Next the pistons go up to scavenge the gases of explosion and draw in fresh 85 vapor for the intermediate explosion chamber. On the next down stroke, fresh explosive vapor is taken in above the pistons, at the end of which stroke the explosion between the piston 18 and head 24 furnishes 90 power to compress the main charges.

Having now explained my improvements, what I claim as my invention and desire to secure by Letters Patent is:—

1. In an explosion engine, the combination of a cylinder, an upper head for the same, an intermediate head having a central opening, a piston rod slideable through said opening, a piston mounted on the rod on either side of said intermediate head, said cylinder having ports to admit explosive vapor at each side of the intermediate head and adjacent the upper head, and valves to control the admission of said vapor. 95

2. In an explosion engine, the combination of a cylinder having intake ports, a head at one end of the same, an intermediate head and pistons within said cylinder forming three explosion chambers, and 100 valves to control the passage of the vapor to said chambers. 110

3. In an explosion engine, the combination of a cylinder having a head at one end of the same, an intermediate head and pistons within said cylinder forming three explosion chambers, and means for effecting 115 the explosions in said chambers.

4. In an explosion engine, the combination of a cylinder having exhaust ports, a head at one end of the cylinder, an intermediate head and pistons within said cylinder forming three explosive chambers, a valve to permit the exhaust from the intermediate chamber; and means operable by the 120 pressure in an adjacent chamber to open said valve. 125

5. In an explosion engine, the combination of a cylinder, an upper head for the same, an intermediate head having a central 130

opening, a piston rod slideable through said opening, a piston mounted on the rod on either side of said intermediate head, said cylinder having ports to admit explosive vapor at each side of the intermediate head and adjacent the upper head and exhaust ports to permit the escape of the vapor, valves to control the admission of said vapor, and a second series of valves to control the escape of the burned gases.

6. In an explosion engine, the combination of a cylinder having intake and exhaust ports, a head at one end of the same, an

intermediate head and pistons within said cylinder forming three explosion chambers, 15 valves to control the passage of the vapor to said chambers, and a second series of valves to control the escape of the burned gases.

In testimony whereof I have signed this 20 specification in the presence of two subscribing witnesses.

GUY R. PRICE.
